UNITED STATES PATENT OFFICE

ALFRED L. SCHELLHAMMER, OF WARREN, PENNSYLVANIA.

RADIATOR-CASING.

No. 920,665.

Specification of Letters Patent.

Patented May 4, 1909.

Application filed March 7, 1908. Serial No. 419,717.

To all whom it may concern:

Be it known that I, ALFRED L. SCHELLHAMMER, citizen of the United States, residing at Warren, in the county of Warren 5 and State of Pennsylvania, have invented certain new and useful Improvements in Radiator-Casings; and I do hereby declare the following to be a full, clear, and exact description of the invention, such as will 10 enable others skilled in the art to which it appertains to make and use the same.

My invention relates to heating devices and more particularly to those which are used in systems in which indirect radiation 15 enters as a factor.

The object of my invention is to produce a casing for a radiator, which may be termed a knock down casing, of simple and inexpensive construction. My improved casing 20 is so constructed as to make it possible to ship it in sections closely packed together, and it may be set up in place by any ordinary workman and without the use of nails or screws.

Another object which I have in view is to 25 force the cold air entering the casing into close contact with the radiator, so that there will be no eddies, but on the contrary a constant outgoing stream of air thoroughly heated by the radiator.

In order that my invention may be clearly understood, I have illustrated it in the accompanying drawings, described it in the specification following, and have more particularly pointed it out in the claims at the 35 end thereof.

Figure 1 of the drawings is a perspective view of my improved casing in operative position. Fig. 2 is a front elevation of the 40 casing with the outer side removed. Fig. 3 is a similar view with both front sides removed. Fig. 4 is a cross section of the casing. Figs. 5 and 6 are detail views of parts of my device. Fig. 7 is an inferior view of 45 a modification of my casing. Fig. 8 is a perspective view of the cold air distributor, forming a part of my device, and Fig. 9 is a similar view of a modification of the same. Fig. 10 is a detail view showing the frame 50 grooved.

Similar letters of reference indicate identical parts throughout.

A represents a rectangular frame which 55 may be made of any desirable material, but which for convenience I have shown as made of wood. This frame is designed to be

firmly secured to the ceiling of a cellar or basement room in which the heating apparatus is located, and may be fastened to the joists of the room above in any desired manner.

The outer edges of the frame are provided with covering of sheet material, preferably galvanized iron, *a* which is preferably flanged outwardly at the upper sides 65 of the frame, and bent inwardly at a right angle somewhat below the lower surface of the frame and then outwardly upon itself forming a continuous longitudinal slot or groove *a'* which extends entirely around the 70 edges of the frame *A*, forming a joint *X*. I may if I desire, instead of this construction, omit the metal covering and form a groove in the edges of the frame itself.

The space *a*² above the bent in portion of the covering, is designed to receive the top *B* of the casing, and hold it in place. The edges of the frame *A* are also provided at intervals with pivotally mounted spring clips *b*, 75 or other suitable retaining devices.

C represents a radiator of any desired construction, which is designed to be supported by rods *c* suspended upon cross rods or sections of gas pipe *c'* set in the joists 85 of a building, the rods *c* being provided at their lower ends with cross rods or channel irons *c*² which are adjustably held in place by nuts *c*³ fitting the screw threaded ends of said rods. Upon the channel irons *c*² the 90 radiator rests. The rods pass through annular openings in the frame *A*, and it is obvious that by providing collars and set screws, the said rods may be made to support the frame if desired.

The casing is provided with double side walls, an air space being left between them. The inner side walls *D*, *D* extend downwardly from the top of the casing to the base of the radiator and rest upon the channel irons *c*² and are held in place vertically by the rods *c* which pass outside of said inner walls by the radiator.

The ends of the casing are preferably covered with asbestos paper, or other non-conducting material. The edges of the bottom *F* of the casing are bent inwardly and outwardly upon themselves in a manner similar to that already described in connection with the covering for the edges of the frame *A*, 105 so as to form a longitudinal groove extending around the outside of the bottom of the

casing. The bottom is also provided with clips b . All the edges of the sides D', D' are bent inwardly, as are also the top and bottom edges of the ends of the casing.

5 The side edges of the ends are bent inwardly and outwardly upon themselves to form a groove extending vertically at the corners of the casing. The ends are also provided with the clips b near their side edges.

10 In the construction shown in Fig. 2, at the end of the casing at which cold air is admitted, I provide an inner end wall G which extends from the frame A to the base 15 of the radiator, and is joined to the inner side walls D, D .

15 The air distributor I , is removably secured to the inner wall G , preferably in the manner already described, by means of the joint 20 X . The distributor may consist of a perforated plate or a wire screen, and extends entirely across one end of the casing, as shown in Fig. 4.

25 Within the casing I provide two baffle plates E and K . The plate E is adapted to rest on the radiator at the forward end of the casing and extends diagonally upward toward the other end of the casing, being inserted in the space a^2 .

30 A hinged flap g is provided on the inside of the wall G and extends along its entire width; the free end of the flap rests on the top of the plate E and prevents the air from passing between the radiator and the wall G .

35 The baffle plate K is located under the radiator, one end resting on the bottom of the casing and the other end upon a vertically adjustable support k , clearly shown in Fig. 6. The plate K is bent upward and backward at an angle at its rear end, as at k^2 , 40 to force the cold air into contact with the radiator.

45 It will be noted that the distance between the rear ends of the baffle plates is greater than that between their forward ends, to accommodate the expansive force of the heated air as it contacts with the radiator.

50 The casing is so designed as to size, that the radiating points i of the radiator will be very close to, but will not quite touch, the inner side walls of the casing.

55 Suitable inlet openings L and outlet openings M are provided in the front and rear walls of the casing for the passage of air currents, but they may be located elsewhere however.

60 In putting my improved casing together, the frame A is first firmly secured to the joists in the ceiling. The hanger rods are then put in place, passing through the holes provided therefor in the frame. The channel irons are then placed on the rods and the radiator is put into position thereon.

65 The inner side walls are next placed, being inserted between the rods and the radiator.

The baffle plate E is then put in place as shown. The ends of the casing are then placed, the bent in edges being inserted in the longitudinal groove a^2 and held by turning the spring clips b . The bottom of the 70 casing is then put in place and also the baffle plate K . The inner front wall is then placed and the distributor secured thereto. The outer sides are then put in place, the bent in edges being inserted in the horizontal 75 and vertical grooves a^2 and the casing is complete, and practically air tight owing to the tight joints formed by the grooves and the insertion of the edges of the sides. The sides are held in place by turning the spring 80 clips b .

85 The operation of the device is apparent. Cold air from the outside is admitted to the casing at L , and immediately drops to the bottom of the casing where it passes through the distributor I , by which it is divided into fine streams or currents, and directed through the comparatively narrow throat formed by the forward ends of the two baffle plates E and K . Here it is forced toward the outlet M , but by means of the baffle plates and the inner sides is kept in close contact with the radiator and becomes highly heated, room being allowed for expansion by the widening of the distance between the rear ends of the baffle plates. The heated air passes through the outlet of the casing, whence it may be carried to any desired point of a building.

90 I have shown a single radiator provided 100 with my improved casing, but it is obvious that my casing may be used in systems, and a number of radiators and casings used, each casing communicating with a room of a 105 building.

110 What I claim and desire to secure by Letters Patent is:—

1. The combination with a casing provided with an air flue extending in an upwardly inclined direction, of a radiator located in a single horizontal plane in said air flue, said air flue having an air inlet below the plane of the radiator and an air outlet, the position of the radiator forming an air space above the same, increasing in size toward the said outlet, and an air space below, increasing in size toward the inlet, whereby the air is forced to pass through the radiator, substantially as described.

115 2. The combination with a casing provided with an air flue extending in an upwardly inclined direction, of a radiator located within the flue in a single horizontal plane, said air flue having an air inlet below the plane of the radiator and an air outlet and means for preventing the air entering the flue from passing around the ends of the radiator whereby said air is forced to pass through the radiator, substantially as described.

3. The combination with a casing provided with an air flue extending in an upwardly inclined direction, of a radiator located within the flue in a single horizontal plane, said air flue having an inlet below the plane of the radiator and an air outlet, the position of the radiator forming an air space above the same increasing in size toward the said outlet and an air space below it, increasing in size toward the inlet, the said inlet being provided with a perforated member in close juxtaposition to the said radiator to diffuse the incoming currents of air immediately upon entering the flue, substantially as described.

4. The combination with a radiator, of a casing surrounding the same, and provided with air inlet and outlet ports, baffle plates located above and below the radiator, and extending diagonally within said casing, and means for admitting air into the space between the baffle plates, the distance between the lower ends of said baffle plates being less than the distance between their upper ends, substantially as described.

5. In a radiator casing, the combination with a frame adapted to be secured to the ceiling of a room, and provided with grooved portions at its outer edges, vertical walls adapted to inclose a radiator, and provided with flanges adapted to engage the grooved portions of the frame, two of said vertical walls being provided with grooves extending vertically at their edges, and adapted to be engaged by vertical flanges on the other two walls, a bottom provided with a longitudinal groove extending entirely around its edges and adapted to be engaged by flanges provided on the four vertical walls, and means for removably securing the said flanges in said grooves, substantially as described.

6. In a radiator casing, the combination with a frame adapted to be secured to the ceiling of a room, a covering for said frame, the outer edges of which are bent inwardly and outwardly to form a groove, a bottom, the edges of which are bent in a similar manner to form a groove, two vertical walls, the vertical edges of which are bent in a similar manner to form vertical grooves, two vertical walls provided with projections to engage the vertical grooves, all of said vertical walls being provided at their upper and lower ends with projections to engage the grooves of the frame and bottom, said projections and grooves being of such relative size as to admit of the ready insertion of said projections into said grooves and their removal therefrom and means for removably securing the said flanges in said grooves, substantially as described.

7. The combination with the outer walls of a radiator casing, of inner side walls extending from one end nearly the length of the casing, an end wall connecting the free

ends of said inner side walls and forming therewith an inner casing, the outer walls of the casing extending below the walls of the inner casing, a top for said casing and a bottom secured to the walls of the outer casing, said outer casing being provided with an air inlet to the space between the ends of the outer and inner casing and an outlet, substantially as described.

8. The combination with the outer walls of a radiator casing, of inner side walls extending from one end nearly the length of the casing, an end wall connecting the free ends of said inner side walls and forming therewith an inner casing, the outer walls of the casing extending below the walls of the inner casing, a top for said casing and a bottom secured to the walls of the outer casing, said outer casing being provided with an air inlet to the space between the ends of the outer and inner casing and an outlet, a radiator supported within the inner casing, and a baffle plate extending from the end wall of the outer casing to the end of the radiator, whereby a pocket or dead air space is formed between the end of the radiator and the end of the casing, substantially as described.

9. In a radiator casing, the combination with a frame, a top secured to said frame, a radiator, supports for the same, three inner walls partially surrounding said radiator, outer side walls removably secured to said frame, said side outer walls extending below the inner walls, a bottom adapted to be removably secured to the outer side walls, a baffle plate adjustably secured to one of the side walls, and located below the radiator, a baffle plate above the radiator, and a movable flap secured to one of the inner walls, the free end of said flap resting on the upper baffle plate, and air inlet and outlet ports to and from the space between the baffle plates, substantially as described.

10. A knockdown radiator - casing comprising top bottom side and end walls arranged and adapted to be separably interlocked, in combination with an air flue in said casing, a radiator adjustably suspended within said flue, and means providing for the passage of air through the flue and in contact with the radiator, substantially as described.

11. A knockdown radiator - casing comprising top bottom side and end walls arranged and adapted to be separably interlocked, in combination with a radiator adjustably suspended within the casing, means for admitting air to and discharging it from the casing, and a baffle-plate arranged to cause the air to traverse the radiator longitudinally, substantially as described.

12. A knockdown radiator - casing comprising top bottom side and end walls arranged and adapted to be separably inter-

locked, in combination with a radiator adjustably suspended within the casing, means for admitting air to and discharging it from the casing, and a vertically adjustable baffle-plate arranged to cause the air to traverse the radiator longitudinally, substantially as described.

13. A knockdown radiator - casing comprising top bottom side and end walls arranged and adapted to be separably interlocked, in combination with an air flue in said casing, a radiator within said flue, means for suspending the casing in operative position and for adjustably suspending the radiator within the casing, and means providing for the passage of air

through said flue and in contact with the radiator, substantially as described.

14. A knockdown radiator - casing comprising top bottom side and end walls arranged and adapted to be separably interlocked, in combination with an air flue in said casing, a radiator within said flue, and means for directing an air supply through said casing and flue and in contact with the radiator, substantially as described.

In testimony whereof I affix my signature, in the presence of two witnesses.

ALFRED L. SCHELLHAMMER.
